FIG. 3.

Patented Aug. 7, 1923.

1,464,356

UNITED STATES PATENT OFFICE.

PETER FEDORYSZAK, OF WALLINGFORD, PENNSYLVANIA.

FLYING MACHINE.

Application filed June 14, 1922. Serial No. 508,220.

To all whom it may concern:

Be it known that I, PETER FEDORYSZAK, a citizen of Ukraine, residing at Wallingford, in the county of Delaware and State of Pennsylvania, have invented certain new and useful Improvements in Flying Machines, of which the following is a specification.

This invention relates to certain new and useful improvements in flying machines and has particular reference to a machine embodying rigid plane sections and hingedly mounted wings disposed above the plane sections adapted for operation at will of the pilot to effect a sudden or rapid ascension of the plane whenever desired.

The invention further embodies in a flying machine of the type above set forth, the provision of devices for connecting the wings to the driving mechanism for the propeller, and further embodies means for holding the wings rigidly positioned at the desired angle relative to the plane sections for operating as a biplane.

The wing structure presents novel features by the inclusion of automatically operating pipe or damper valves in the wings to be opened against the spring tension thereon upon rising movement of the wings, and automatically closed when the wings are lowered, thereby offering the least air resistance to the wings when the same are raised and affording a full working surface when the wings are lowered.

With the above general objects in view and others that will appear as the nature of the invention is better understood, the same consists in the novel construction, combination and arrangement of parts hereinafter more fully described, illustrated in the accompanying drawings, and pointed out in the appended claim.

In the drawings forming a part of this application and in which like designating characters refer to corresponding parts throughout the several views.

Figure 1 is a front elevational view of a flying machine constructed in accordance with the invention, showing the rigid plane sections and the hingedly mounted wings disposed above the plane,

Figure 2 is a top plan view of the flying machine showing the tensioned automatically operated damper plate carried by the wings,

Figure 3 is a vertical sectional view taken on line III-III of Figure 4 showing a por-

tion of the operating mechanism for the hinged wings,

Figure 4 is a vertical sectional view taken on line IV-IV of Figure 3 showing the 60 crank shaft and connecting rods attached to the sliding frame bar for reciprocating the wings and connecting the crank shaft of the wing operating mechanism to the driving mechanism of the flying machine propeller, 65

Figure 5 is a detail sectional view taken on line V-V of Figure 3 showing the sliding frame bar and the guide bars therefor,

Figure 6 is a detail sectional view taken on line VI-VI of Figure 4 showing the 70 mechanism for holding the wings rigidly positioned,

Figure 7 is a detail fragmentary edge elevational view of the sliding frame bar, showing the anti-friction roller carried 75 thereby, and

Figure 8 is a fragmentary detail sectional view of a portion of the wings showing the tensioned automatically operating damper plate carried thereby.

Referring more in detail to the accompanying drawings, and with particular reference to Figures 1 and 2, there is illustrated a flying machine embodying a fuselage 1 provided with the usual empennage 2 at the rear end thereof, the power shaft for the motor carried in the fuselage extending through the forward end thereof for supporting a propeller 3 while rigid planes 4 extending laterally of the fuselage are suitably braced by truss rods 5, an operator's seat 6 being positioned in the fuselage rearwardly of the planes 4 as clearly shown in Figures 2 and 6.

A hinged wing structure is supported 85 above the rigid planes 4, a standard embodying a cross head 7 having spaced perpendicular depending side legs 8 carrying angle feet 9 at the lower ends thereof to be secured as at 10 to the opposite sides of the fuselage 100 1 as clearly shown in Figures 3 and 4. A hinged plate 11 is secured to the upper end of the cross head 7 and has hingedly connected to each side thereof, a wing 12.

The wing is of oval formation in plan 105 view and is curved transversely of the longitudinal sections thereof, each wing being provided with a pair of openings 13 normally closed by damper plates 14 hinged as at 15 adjacent opposite sides of said openings, a pair of flat springs 16 secured as at 17 to the under face of the wing 12 having

the free ends thereof engaging the damper plates 14 for normally holding the same in closed position shown in Figure 2.

The operating mechanism for the hinged 5 mounted wings 12 includes a skeleton frame bar 18 vertically slidable between the side legs 8 of the supporting frame for said wing, the opposite ends of the frame bar 18 being reduced as at 19 and carrying anti- 10 friction rollers 20 that engage the legs 8 as clearly shown in Figures 3, 5 and 7. An attaching clip 21 secured to each side of the frame bar 18 has pivotally mounted therein, one end of a link 22 that has the 15 other end thereof pivotally connected as at 23 to the under face of the wing 12. A shaft 24 having a crank portion 25 is journaled transversely of the fuselage 1 as shown in Figures 4 and 6, one end of the 20 crank shaft 24 carrying a sliding clutch element 26 for connecting said shaft to the sprocket wheel 27 driven by a chain 28 connected to the motor for operating the propeller 3. A link rod 29 connected as at 25 30 at its lower end to the crank portion 25 of said shaft has the upper end thereof pivotally connected as at 31 to the lower side 35 of the frame bar 18.

To hold the wing 12 rigidly positioned, 30 when the clutch element 26 is disengaged from the sprocket wheel 27, the gear wheel 32 fixed to the crank shaft 24 at one end thereof is adapted to be engaged by the sliding bolt rod 33 guided in brackets 34 as 35 shown in Figures 4 and 6.

In the operation of the device, the propeller is operated by the motor supported in the fuselage, the rigid planes 4 and the empennage 2 controlling the flight of the 40 machine. When it is desired to suddenly rise or increase the lifting power of the machine, the clutch element 26 is moved into engagement with the sprocket wheel 27 connected to the power mechanism of the 45 machine, thereby rendering the crank shaft 24 operative for vertically reciprocating the same bar 18 and swinging the wings 12 upon their hinge connections with the upper end of the cross head 7 of the supporting 50 frame as clearly illustrated. During the rising movement of said wings, the damper

plates 14 will be opened against the tension of the flat springs 16 to offer the least resistance to air pressure, and upon downward movement of said wings, the damper plates 55 will be closed to offer greater resistance to the air pressure and thereby insure a more certain rise of the machine. The wings 12 may be set in rigid position as indicated by the arrow lines in Figure 1, and so retained by the sliding bolt rods 33 engaging the gear wheel 32 above the crank shaft 24, such connection being effected when the clutch element 26 is disengaged from the power sprocket gear 27. Friction between 60 the movable parts of the device are minimized by the provision of the anti-friction rollers 20 between the cross bar frame 18 and the guide legs 8.

While there is herein shown and described what is believed to be the preferred embodiment of the invention, it is nevertheless to be understood that various forms, modifications and arrangements of the parts may be made without departing from the 75 spirit and scope of the invention as claimed.

Having thus described the invention, what I claim as new is:—

In a flying machine of the type described, a fuselage, a plane section rigidly carried thereby, a perpendicular guide frame superposed on the fuselage, side wings hinged to the upper end of the supporting frame, a frame bar vertically slidable in said support, link rod connections between the frame bar and the wings, a crank shaft journaled transversely of said fuselage, a link rod connection between the crank portion of said shaft and the frame bar, and connections between the flying machine motor and the crank shaft, means for disconnecting the crank shaft from said motor and means for holding the crank shaft rigidly positioned with the wings immovable, said last mentioned means comprising a gear wheel 80 fixed to said crank shaft, guide brackets 85 carried by said fuselage, and a sliding bolt rod carried by said brackets and adapted for engaging said gear for holding the crank shaft rigidly positioned.

In testimony whereof I affix my signature.
PETER FEDORYSZAK.
